UNITED STATES PATENT OFFICE.

WALTER F. WARE, OF CAMDEN, NEW JERSEY.

SUSPENSORY BANDAGE.

SPECIFICATION forming part of Letters Patent No. 375,846, dated January 3, 1888.

Application filed April 7, 1887. Serial No. 233,987. (No model.)

To all whom it may concern:

Be it known that I, WALTER F. WARE, a citizen of the United States, and a resident of Camden, New Jersey, have invented an Improvement in Suspension Bag and Receptacle for the Penis and Testicles in Cases of Disease; and I do hereby declare the following to be a full, clear, and exact description of the same, reference being had to the annexed drawings, making part thereof.

My invention is designed to be used in cases of disease of the human private organs to suspend them, prevent friction with the limbs, and to receive discharges.

It consists, speaking generally, of a bag with a buttoned flap in front and adapted to contain cotton or some absorbent of the matter discharged, and is held up by a strap around the waist of the wearer. Attached to the back of this bag is another and smaller one of net-work sustained by bands tied or otherwise secured to the main band, which passes around the person of the wearer.

In the drawings, Figure 1 is a rear elevation of my device; Fig. 2, a front elevation of the same; Fig. 3, a vertical sectional view showing the flap buttoned.

A is the bag for the penis; B, an opening to receive the latter; C, the front flap provided with button-holes D D, the buttons E E being in front of the main strap F, the latter being provided with a buckle, G; H, the net-work bag at the back of bag A to receive and sustain the testicles; I, two bands to be secured to strap H on either side of the bags to sustain bag H; J, a mass of cotton or other material to receive and absorb the gonorrhœal or other discharge of the diseased person.

The bags are attached to the person of the wearer as follows: The penis is thrust through the hole B, so as to hang suspended in bag A,

and the testicles are rested in bag H. Strap F is then passed around the waist and buckled in place, or buttoned, if desired, the buckle being preferred, as it will suit different-sized wearers. Bands I I are then passed around the buttocks and tied to the waist-belt F to hold up the bag H, and the device is affixed. If it is desired to urinate or remove cotton J, the flap C is unbuttoned and allowed to fall down, thus offering free access to the interior.

My bag A is made of linen or other porous fabric, so that the air will circulate freely through the material. I thus keep the parts cool and allay inflammation and all tendency thereto.

The old air-tight bags made of oiled silk, rubber, &c., retain the heat and perspiration, thus keeping up an irritation. My bag also dispenses with the necessity for tight wrapping, and saves the clothing and bedding from being soiled by the discharge.

In cases of gonorrhœa the testicles very frequently swell. It is therefore highly important that the two bags A and H should be used in conjunction.

What I claim as new is—

1. In a suspension device, the bag A, provided with opening B, front drop-flap, C, and waist-strap F, substantially as and for the purpose described.

2. In a suspension device, the combination of bag A, to receive the penis, provided with opening B, and front drop-flap, C, having fastenings E E, bag H, for the testicles, attached to back of bag A, and suspension bands I I, substantially as for the purposes described.

WALTER F. WARE.
